UNITED STATES PATENT OFFICE.

JOHN L. STAGG AND CHARLES W. FENN, OF CHICAGO, ILLINOIS, AND
CHARLES T. SCHOEN, OF ALLEGHENY, PENNSYLVANIA.

VENTILATED CAR-DOOR.

SPECIFICATION forming part of Letters Patent No. 487,163, dated November 29, 1892.

Application filed April 7, 1892. Serial No. 428,224. (No model.)

To all whom it may concern:

Be it known that we, JOHN L. STAGG and CHARLES W. FENN, residing at Chicago, in the county of Cook, in the State of Illinois, 5 and CHARLES T. SCHOEN, residing at Allegheny, in the county of Allegheny and State of Pennsylvania, citizens of the United States, have invented a certain, new and useful Improvement in Ventilated Car-Doors, of which the following is a full, clear, and exact description.

The object of this invention is to provide an economical and efficient ventilating-door principally for use in box or freight cars. In 15 box-cars it is oftentimes necessary to close their openings tight against the admission of air and at other times it is equally necessary to provide for a free circulation of air in them. For economical and other reasons it is desirable to have as few openings in and additions 20 to such and other cars as possible, and so we utilize the necessary doors for ventilation as well as security, and while we herein show and describe our invention as embodied in a 25 door only, nevertheless we wish to be understood as not thereby restricting the use of its essential features and characteristics to doors, for it is obvious that the ventilators may be applied as well in the sides and ends of cars 30 and elsewhere and in other objects as in doors.

In the accompanying drawings, illustrating our invention, in the several figures of which like parts are similarly designated, Figure 1 is an elevation with one of the hooded plates 35 broken away; and Figs. 2 and 3, sections taken, respectively, in the planes of lines xx and yy of Fig. 1.

We prefer to construct our door with stiles a , three rails b , and mullions c , so as to provide 40 four panels; but of course we do not limit our invention to such a door; also, we prefer to unite the stiles and rails by joint-bolts, as indicated by the dotted lines. In our invention the panels d are ventilators, 45 which may be opened and closed at pleasure. These panels we prefer to construct of steel plate or other wrought metal; but we prefer steel plate because of its lightness, strength,

and stiffness. We use in each panel a plate e , fixed in between the stile, mullion, and rails 50 adjacent thereto and having the inclined lower edge f to shed water, &c. This plate is provided with a number of holes g , preferably oblong, as shown in Fig. 1. A sliding or movable plate i is arranged over this plate e and 55 is secured to it by pins j and slots k , and said plate i is provided with hooded holes l to register with the holes g in plate e . The hooded holes are formed by slitting the plate and 60 pressing, punching, stamping, or drawing up the hoods, and in order to straighten and stiffen the plate after such operation of forming the hooded openings we form a bead or 65 rib m around its margin. A gravity-button n is pivoted to the lower edge of the hooded plate. Normally the hooded plate uncovers 70 all the openings. When it is desired to cover the openings, the hooded or sliding plate is raised and its button dropping rests upon the lower edge of the fixed plate and so holds the 75 said hooded plate closed. Other means than the gravity-button may be employed for holding up the movable or sliding plate. Each hooded plate is capable of independent operation, and hence the ventilation may be from 80 the top or bottom or at both points. The hoods are provided to exclude the sun's rays, 85 snow, sleet, and rain while freely admitting air. We have shown the fixed plate secured in rabbets in the doors by means of moldings 80; but we do not limit our invention thereto. The sliding plate may be arranged to close or open the fixed plate in normal position, and so, also, it may be raised to open the ventilator or to close it, or it may be lowered to open or 85 close it.

What we claim is—

1. A ventilating-door having fixed perforated plates at top and bottom and sliding perforated plates applied to such fixed plates 90 by means of slots and pins and normally having their perforations in register, substantially as described.

2. A ventilating-door having a series of panels, each composed of a fixed perforated 95 metal plate and a sliding plate applied there-

to and supported by it by means of slots and pins and having hooded openings normally registering with the openings in the fixed plate and adapted to be moved to close the 5 openings in the fixed plate and to be held in such closing position, substantially as described.

3. A ventilator having a fixed perforated metal plate and a sliding plate applied there-
10 to and supported by it by means of slots and pins and having hooded perforations and adapted to be moved to open or close the perforations in the fixed plates, substantially as described.

In witness whereof we have hereunto set 15
our hands.

JOHN L. STAGG.

CHARLES W. FENN.

CHARLES T. SCHOEN.
